UNITED STATES PATENT OFFICE.

FRANKLIN M. SAUBER, OF LANCASTER, PENNSYLVANIA.

DESIGN FOR A CAMPAIGN-BADGE.

43,370.

Specification for Design.

Patented Dec. 24, 1912.

Application filed August 7, 1912. Serial No. 713,946. Term of patent 3½ years.

To all whom it may concern:

Be it known that I, FRANKLIN M. SAUBER, a citizen of the United States, residing at Lancaster, in the county of Lancaster and State of Pennsylvania, have invented a new, original, and ornamental Design for a Campaign-Badge, of which the following is a specification, reference being had to the accompanying drawing, forming part thereof.

The figure is a front elevation of a campaign badge, showing my new design.

I claim:

The ornamental design for a campaign badge, as shown.

FRANKLIN M. SAUBER.

Witnesses:

WM. J. COULTER,
MABEL L. LEFEVRE.
